UNITED STATES PATENT OFFICE.

GEORGE HILGER, OF CHICAGO, ILLINOIS.

DISPLAY CASE.

Application filed November 8, 1920. Serial No. 422,444.

To all whom it may concern:

Be it known that I, GEORGE HILGER, a citizen of the United States, residing at Chicago, in the county of Cook and State of Illinois, have invented certain new and useful Improvements in Display Cases, of which the following is a specification.

The invention pertains to display cases for containing food products, such as meat, which must be kept at a low temperature in order to be properly preserved.

The general object of the invention is to provide a refrigerating system for show cases of a highly efficient character.

A further and more specific object of the invention is to provide a display case of the type indicated having means for maintaining a constant supply of cool dry air in the upper portion of the case in which is located the food products to be preserved.

Another object of the invention is to provide improved means for supporting the food products in the case in such a manner as to be readily accessible.

Still another object of the invention is to provide a display case of the type referred to which is capable of easy attachment to counters in use as well as to counters in the course of construction.

To produce a construction capable of obtaining the objects of the invention thus set forth in a practical manner is a further and ancillary object of the invention.

In the drawings, Figure 1 is a transverse vertical section through a display case embodying my invention, the case being shown in position upon the upper end of a counter such as is employed in meat markets and the like. Fig. 2 is a horizontal section taken in the plane of line 2 of Fig. 1 but on an enlarged scale. Fig. 3 is a fragmentary vertical sectional view through a portion of the refrigerating system illustrating the manner in which a two-pipe vertical conductor for the refrigerant is interposed in a continuous pipe line, the view being taken substantially in the plane of line 3 of Fig. 2. Fig. 4 is a plan view of a swinging supporting frame mounted in the case. Fig. 5 is a vertical sectional view through said frame and a tray mounted thereon illustrating the manner in which the free end of a frame is

mounted for swinging movement. Fig. 6 is a fragmentary longitudinal vertical section taken substantially in the plane of line 6 of Fig. 1. Fig. 7 is a horizontal sectional view through the case but showing a slightly different embodiment of the invention. Fig. 8 is a perspective view of the arm which serves as a connecting link between the frame and the door of the case and also as a means for supporting the free end of the frame in the swinging movement thereof.

Referring to Figs. 1 and 6 of the drawings, 10 designates the upper portion of a counter the top of which has been removed to permit of the insertion into its upper end of my improved display case. Such case comprises generally a base portion 11 providing a tank 12 for the reception of a cooling medium, and an upper portion 13 of glass or other suitable material having a door 14 at its rear side. Supporting means, designated generally 15, is swingable in a horizontal plane into and out of the case and preferably connected with the door so as to be operable thereby. 16 designates a coil of piping adapted to conduct a refrigerating agent through the base of the case 80 for the purpose of absorbing heat from the cooling medium in the tank; and 17 and 17^a designate two-pipe conductors interposed in the pipe line of the coil and extending upwardly into the upper portion 13 of the case to absorb the heat therein.

The base 11 of the case is preferably of double-wall construction, formed by metallic sheeting 18 spaced apart to receive a filler 19 of suitable insulating material, such as cork; and the base is shaped to provide laterally extending flanges 20 adapted to rest upon the upper edges of the counter 10 while the base proper depends into the counter.

The upper portion 13 of the case is constructed in any suitable and well known manner, but preferably of glass, and is secured to the base so as to be rigid therewith. In its rear portion, said upper portion has a door 14 mounted to swing on a vertical axis, as shown at 21. In Figs. 2 and 6 I have shown the case as having mounted therein two swinging supporting means 15, which

are identical in construction except that one is adapted for the left-hand side and one for the right-hand side. Accordingly, only one of such means need be described. When 5 two supports are employed, I of course provide two doors 14 with which the supports are operatively connected for swinging movement, as will be hereinafter set forth.

As shown in Figs. 2 and 6, I prefer to 10 construct the case in relatively short lengths capable of being mounted end to end to form a continuous case of any desired length and capacity. In the event that more than one section is employed, the counter 15 is provided with suitable partitions 22 upon which the end flanges 20 of adjoining case sections are adapted to rest; and the construction of the upper sections of each of the cases is such as to provide for the connection 20 of the adjacent case sections with a partition 23 therebetween.

The supporting means 15 for the food products to be preserved preferably comprises a swinging supporting frame 24 25 formed of metal and of open work construction, and a top plate or tray 25 adapted to be removably mounted upon the supporting frame. Upon this tray 25 is placed the food products to be preserved. The supporting 30 frame 24 is swingably mounted upon the upright conductor 17 as an axis, and to this end the frame is provided near one corner thereof with a bearing or bushing 26 adapted to receive the conductor 17. The bushing 35 26 is mounted upon a ball bearing 27 which in turn rests upon the upwardly extending stem of a T-fitting 28 in the coil 16.

The coil 16 (Figs. 2 and 7) enters the case at one end thereof, as shown at 29, and 40 leaves the other end at the opposite corner, as shown at 30, and a plurality of T members 28 are interposed in the pipe line between the inlet and outlet for each case and constructed to permit of the passage of the 45 refrigerating agent through the conductors 17 and 17^a, as hereinafter set forth.

Stationarily mounted on the pipe coil 16 is a track member 31, arcuate in form, upon which a roller 32 mounted upon the 50 under side of the free end of an arm 33 is adapted to travel. Said arm is pivotally connected to one end of the door 14 near the lower portion thereof, and at its opposite end carries an upright pin 34 adapted 55 to enter a boss 35 depending from the frame 24. The frame has a plurality of cross bars 36 by which the bushing 26 and boss 35 are carried, and between two of these cross bars of the frame is mounted a roller 37 which 60 is adapted to operatively engage the upper surface of the arm 33 (Figs. 2 and 5).

It will be seen that as the door 14 is 65 swung outwardly, the supporting frame 24, together with the tray 25, also swings outwardly, and in this movement the frame is

supported at its free end by the roller 32 operating on the track 31 and by the roller 37 operating upon the arm 33. Thus it will be seen that in the same movement, the door 14 is opened and the food products mounted upon the tray 25 are carried outwardly of the case to an accessible position. 70

For the purpose of securing the door in its closed position, a suitable spring latch 38 may be employed, and preferably such latch 75 is of a type that when the handle is grasped and pulled forwardly, the latch is released.

The two-pipe conductors 17 and 17^a each 80 comprises an inner pipe section 39 and an outer pipe section 40. The inner pipe section has its lower end threaded into a web or partition 41 formed in the T-fitting 28, and the lower end of the outer pipe section 40 communicates with a nipple 42 which is threaded into the upper or stem end of the fitting. The opposite ends of the cross portion of the fitting are connected with the piping of the coil 16, as will be readily understood. It will thus be observed that the arrangement is such that the refrigerating agent passing through the pipe coil 16 in the direction of the arrow shown in Fig. 3 finds its way through the nipple 42 into the outer pipe section 40 and in its expansion absorbs the heat from the atmosphere in the upper section 13 of the case and thence finds its way out through the inner pipe section 29 and the opposite end of the fitting from whence it travels through the piping to the next conductor, and finally 95 to the compressor. By this construction and arrangement it will be apparent that not only is the heat withdrawn from the cooling medium contained in the tank 12, but it is also withdrawn from the upper portion of the case. The air coming in contact with the outer pipe section 40 of the two pipe conductors, tends to travel downwardly (see arrows in Figs. 1 and 6) along the conductors, and at points removed from the conductors, the air tends to travel upwardly. To permit of such circulation of 100 the air around the conductors 17 and 17^a, the apertures 25^a in the trays 25 through which the conductors pass are made of substantially greater diameter than the conductors as shown in Figs. 2, 3 and 7. It will also be apparent that any moisture in the atmosphere in the upper section 13 of the case will accumulate upon the outer pipe section 40, so that the air is maintained in a substantially dry state and hence moisture and frost will not accumulate upon the meat or other food products supported by the tray. Referring to Figs. 2 and 7, it 110 will be seen that the conductors 17^a are located at the corners of the supporting means 15, the latter being suitably shaped to permit of their swinging movement into and out of the case. 115

120

125

In the embodiment of the invention shown in Fig. 7, a single supporting means 15 is mounted in a section of the case, the latter being in this instance made relatively 5 shorter than where two of the supporting means 15 are employed. The supporting frame 24', the tray 25' and the coil 16' are accordingly made of somewhat greater dimensions than where two of the supporting means are employed. The operation, 10 however, is identical in each instance.

The operation of the refrigerating system will, it is believed, be understood from the foregoing. The refrigerating agent, 15 such as ammonia gas, is introduced into the coil 16 through the inlet 29 which leads either from the coil in the next adjacent section, or from a compressor or other source of gas supply. From the coil the 20 refrigerant flows through the two pipe conductors 17 and 17^a, which are interposed in the coil so that the gas flows first upwardly into the outer pipe section, in which it expands to absorb the heat and moisture 25 from the atmosphere of the upper portion of the case, and then finds an outlet through the inner pipe section 39 and continues on its way through the coil 16 to the next upright conductor. Finally the refrigerating 30 agent is discharged from the outlet 30 either into the coil of the next adjacent section or is returned to the compressor. By reason of the absorption of the heat and moisture from the upper portion of the display case, 35 the food products are kept free from moisture and otherwise properly preserved. The air in the immediate vicinity of the conductor is cooled and descends to the bottom of the case, and at points removed 40 from the conductors, the air rises as shown by the arrows in Figs. 1 and 6. Thus a continuous circulation of the air is maintained. The passage of the refrigerant through the coils 16 in the base portion of 45 the case tends to absorb the heat from the brine or other cooling medium in the tank 12 so that the lower portion of the case is properly refrigerated.

By the peculiar association of the supporting means for the food products with the door, the operation of withdrawing the food products from the case is greatly simplified and by reason of the saving in time consumed, a saving in the operation of the 55 refrigerating system is effected. The construction of the supporting means and associated parts is also of an advantageous character, the operation being smooth and easy, requiring the expenditure of a minimum of effort.

By reason of the peculiar construction of the case, it will be apparent that it is capable of being quickly and easily mounted upon a counter in use, and the sectional construction of the case is desirable in that

it facilitates the expansion or reduction in the size of the equipment from time to time as conditions may determine.

While I have herein illustrated and described the invention with considerable particularity, it is contemplated that various changes and modifications may be made without departing from the spirit and scope of the invention as expressed in the appended claims.

I claim as my invention:

1. A display case comprising, in combination, a base portion and an upper portion, the base portion providing a tank for the reception of a cooling medium, means for providing a support for food products in the upper portion, a continuous pipe coil mounted in said base so as to be immersed in the cooling medium in said tank, and a conductor extending above said supporting means comprising two pipe sections communicating with each other at one end and connected at their opposite ends with opposed portions of the continuous coil whereby said conductor is interposed in the coil. 90

2. A display case comprising, in combination, a base section, a horizontal conductor in the form of a coil for a refrigerant such as ammonia gas, a support above said coil, and one or more vertical conductors extending into the upper section of the case above said support and comprising two pipe sections disposed one within the other, the inner pipe section being open at its upper end and at its lower end connected with one portion of said coil and the outer pipe section being closed at its upper end and communicating at its lower end with the opposite section of the coil, whereby the flow of gas through the coil and the conductor is 100 continuous. 105

3. A display case comprising, in combination, a display section, a tray or table upon which quantities of food to be preserved may be placed, means for swingably supporting the table in the display section of the case to move about a vertical axis, means located coaxially with said vertical axis of said swinging table for absorbing moisture and heat from the display section of the case, said means including an upright pipe, 110 said table having an aperture for receiving said pipe of greater diameter than the pipe whereby to permit of the passage of air downwardly along the pipe. 115

4. A display case comprising, in combination, a base section, and an upper or display section, a support above the base section, a pipe in the base section having an inlet and an outlet, said pipe having interposed thereon a T-fitting with a dividing web or partition, an upright pipe section extending above said support and communicating at its lower end with the stem of the T-fitting and with one side of the partition and an 125

- inner pipe section opening at its upper end into the outer pipe section and entered at its lower end through said partition so as to communicate with the opposite end of the 5 T-fitting.
5. A display case comprising, in combination, a refrigerating pipe in the lower portion of the case having interposed therein a T-fitting with its stem extending upwardly 10 and having a transverse partition therein, an upright pipe section closed at its upper end and communicating at its lower end with said stem of the fitting, an inner pipe section open at its upper end and entered 15 at its lower end through said partition, and means mounted above the refrigerating pipe in the lower portion of the case coaxially of said pipe sections and bearing upon the stem of said fitting for supporting articles to be 20 preserved.
6. A display case comprising, in combination, a display section, a horizontal pipe mounted in the lower portion of the case and having interposed therein a T-fitting 25 having an upwardly extending stem, a pipe closed at its upper end and communicating at its lower end with said stem, a support in the display section for food or other products to be preserved, and means surrounding said pipe and bearing upon said stem for mounting said support for swinging movement into and out of the case. 30
7. A display case comprising, in combination, a base section and an upper or display section, a horizontal pipe section mounted in the base section and having a T-fitting interposed therein with its stem extending upwardly, means for conducting a refrigerant from said pipe into the display section including a pipe entered at its lower end in 35 said stem of the fitting, a support above said horizontal pipe for the articles to be displayed comprising a frame having a bearing bushing, a bearing interposed between said bushing and said stem of the fitting and surrounding said pipe, and means for moving the frame on said bearing.
8. A display case of the character described comprising, in combination, an upper display section having a swingable frame adapted to support products to be refrigerated and capable of swinging into and 40 out of the case, said display section having a door through which said frame is adapted to move, a refrigerating coil mounted horizontally beneath said frame to permit of the swinging movements thereof, and means carried by said coil for supporting said frame in its swinging movements relative thereto. 45
- 60 9. A display case of the character described comprising, in combination, an upper display section having a swingable frame adapted to support products to be refrigerated and capable of swinging into and out of the case, said display section having a 50 door through which said frame is adapted to move, a refrigerating coil extending horizontally beneath said frame and having a vertical extension terminating above the plane of said frame serving as a pivot whereon said frame is movable, and means carried by said coil to support said frame in its swinging movements relative thereto. 55
10. A display case of the character described comprising, in combination, an upper display section having a swingable frame adapted to support products to be refrigerated and capable of swinging into and out of the case, said display section having a door through which said frame is adapted to move, a refrigerating coil mounted horizontally beneath said frame to permit of the swinging movements thereof, a track on said coil, and a roller on said frame bearing on said track to facilitate movement 60 of said frame relative to said coil. 65
11. A refrigerating display case of the character described comprising, in combination, an upper display section, a swingable table for supporting food products to be preserved mounted to swing into and out of said case, a door opening adjacent said table permitting the passage of said table, a link pivotally connected to said door and table, a refrigerating coil extending horizontally in said case beneath said table, a track on said coil, and a roller on said link bearing on said track to facilitate movement 70 of said support relative to said coil. 75
12. A refrigerating display case of the character described comprising, in combination, an upper display section, a swingable table for supporting food products to be preserved mounted to swing into and out of said case, a door opening adjacent said table permitting the passage of said table, a link pivotally connected to said door and table, a refrigerating coil extending horizontally in said case beneath said table, a track on said coil, and a pair of rollers constituting anti-friction means for facilitating relative movement between the parts when said table is swung relative to said coil, one of said rollers being carried by said table and riding on said link and the other of said rollers being carried on said link and riding on said track. 80
13. The combination with a counter having an open upper end, of a display case having a lower or base portion adapted to fit into and be supported by the said open end of the counter, an upper display section supported upon the base section, said display section having in its lower portion a support for food products and the like adapted to 85 form with the base section a substantially closed chamber, and a refrigeration unit enclosed within said chamber. 90
14. A display case of the character described comprising, in combination, an up- 95

per display section and a lower or base section, a refrigerating coil arranged horizontally in the upper portion of said base section, and a frame mounted directly above said coil in the lower portion of the display section and adapted to swing into and out of the case, said display section having a

door with which said frame is operatively connected so as to move into an accessible position out of the case when the door is 10 opened.

In testimony whereof, I have hereunto set my hand.

GEORGE HILGER.
